UNITED STATES PATENT OFFICE.

HENRY W. O'DOWD, OF JERSEY CITY, NEW JERSEY, ASSIGNOR TO STANDARD GAS EQUIPMENT CORPORATION, A CORPORATION OF MARYLAND.

GAS RANGE.

Application filed September 18, 1925. Serial No. 57,056.

This invention is directed to an improved gas range having a closed smooth-surfaced cooking top and burners located beneath the front and rear portions of the top. Attempts have been made to provide a gas range of this kind by merely substituting a closed top for the open or grid top commonly employed in the ordinary type of gas range. A range as thus constituted is very inefficient, producing imperfect combustion and generating obnoxious carbon monoxide fumes. In the course of experiments it has been found that these objections are due primarily to the fact that when all of the burners are in use, a proper quantity of secondary air fails to reach the rear burners, and moreover such air as does reach the rear burners is badly contaminated by the products of combustion emitted from the front burners.

The present invention is intended to overcome these and various other objections. One of the characteristic features of the improved range is the provision of a burner plate interposed between the burners and the cooking top and which provides in effect two chambers, one an upper shallow combustion or heat generating chamber having an outlet at the rear for the products of combustion, and the other a lower secondary air chamber open at the front and containing all of the burners, those at the front as well as those at the rear. This burner plate is formed adjacent each burner with a secondary air inlet, which in the embodiment illustrated is constituted by a group of openings leading from the secondary air chamber into the heat generating chamber and through which the individual flame jets project. According to this construction, the secondary air is supplied to all of the burners in its pure atmospheric condition and free from contamination by the products of combustion, it being noted that no air enters the heat generating chamber except that which is entrained by the flame jets. Actual practice has shown that a range constructed in this manner is extremely efficient, giving a maximum heating efficiency with a minimum consumption of fuel, and this whether all of the burners are used singly or collectively. This and other improvements will be fully set forth in the detailed description to follow.

In the accompanying drawings:

Fig. 1 is a front elevation of a gas range constructed in accordance with the invention;

Fig. 2 is an enlarged vertical section taken on the line 2—2 of Fig. 1;

Fig. 3 is a sectional plan view on a large scale taken on the line 3—3 of Fig. 1, the cooking top being broken away at the rear to show the interior construction;

Fig. 4 is a plan view of a range like that shown in Fig. 1 but with a modified form of cooking top; and

Fig. 5 is an enlarged transverse section taken on the line 5—5 of Fig. 4.

In the present instance, and as shown in Fig. 1, the invention has been shown as applied to a gas range of the cabinet type, although it is evident that it is equally applicable to a range of any other type. The range whose body is denoted as a whole by the reference numeral 1, is provided at the right with two superposed ovens 2 and 3, at the left with the cooking top 4 located above and in spaced relation to the top wall 5 of the underlying heating compartment 6, and at the rear with the splasher 7, all as usual except that the cooking top is shown as of the closed smooth-surfaced variety contemplated. At this point it may be noted that, at the rear of the splasher 7, the cooking top 4 is formed throughout its length with a series of outlet openings or vents 8 adapted to discharge into a flue 9 the products of combustion which issue from the heat generating chamber underlying the cooking top. This flue 9 extends laterally in the manner indicated by dotted lines in Fig. 1 and is also arranged to receive the products of combustion issuing from the two ovens 2 and 3. The form and arrangement of the flue constitute no part of this invention and hence will not be described further, although if desired reference may be had to my co-pending application, Serial No. 20,023 for greater details.

Coming now to the invention, a burner plate 10 (preferably made of cast iron) is located in the space between the closed cooking top 4 and the compartment top wall 5 and provides in effect an upper unobstructed combustion or heat generating chamber 11 and a lower secondary air chamber 12, the burner plate thus constituting the floor or lower wall of the combustion chamber and the upper wall of the secondary air chamber. As best shown in Figs. 2 and 5, the burner

plate is arranged in close parallel relation to the overlying cooking top so as to provide a shallow combustion chamber which will serve to heat the entire top whether one or 5 more of the burners are in operation at a time. For reasons which will presently appear, the burner plate is designed to exclude secondary air from the combustion chamber except that which is entrained by the flame 10 jets; hence its four edges are turned upwardly to engage the underside of the cooking top (see Figs. 2 and 5). As a convenient means of support for the burner plate, its side edges are formed with flanges 13 secured to the cooking top by bolts 14. As 15 thus supported, the burner plate, being suspended from the top, may be removed as a unit with the top or if desired it may be removed independently of the top by unfastening the bolts 14.

Beneath the burner plate 10 and within the secondary air chamber 12 are mounted a plurality of main heating Bunsen burners 15 (four in the present instance, although 20 the number might be greater or less), two located at the front and two at the rear. These burners may be of any suitable form or type, those herein shown being circular and each formed with a series of gas orifices 25 or flame ports 16 which are vertically disposed so as to direct the flame jets upwardly at right angles to the top and thus allow the burners to be located in close proximity thereto. Extending forwardly from the respective burners are mixing tubes 17 provided with exterior primary air chambers 18 disposed in a row at the front of the range and into which gas is discharged from a common manifold 19 under the control of 30 separate valves or stop cocks 20. As indicated by the dotted lines in Fig. 3, the mixing tubes of the rear burners are bent laterally to clear the front burners since the rear burners are arranged in direct line with the front burners, although they need not be. The mixing tubes 17 are fitted over the nozzles of the gas cocks 20 in the usual way but at the rear the burners proper are detachably suspended from the burner plate 10. 35 This method of supporting the burners is also presented in my copending application Serial No. 20,023, above referred to, and constitutes no part of the present invention.

Directly above the several Bunsen burners 40 15, the burner plate 10 is formed with localized secondary air inlets, one for each burner, these inlets in the preferred embodiment illustrated being in the form of a series of nozzles 21 arranged in vertical alignment with the gas orifices or flame ports 16 and having their bores or openings tapered upwardly as shown in Fig. 2. Preferably and as shown, the gas orifices 16 terminate below, rather than project into, the lower ends of 45 the air nozzles 21, this arrangement pro-

viding for the better aeration of the flame jets and enabling the inflowing air more effectively to insulate the gas orifices from the heat of the flame jets and the hot walls of the air nozzles. As before intimated, the nozzles 21 constitute the sole means for admitting the secondary air to the combustion chamber 11, so that the flame jets in being projected vertically through the nozzle openings are enabled to entrain whatever quantity of secondary air is required to support combustion and no more. The air chamber 12 being entirely open at the front, will furnish an ample supply of secondary air under all conditions of use. It is pointed out (Fig. 2) that the secondary air nozzles 21 are formed upon depressed portions 22 of the burner plate, these depressions serving to catch and drain off grease and other substances which may fall into the combustion chamber from cooking utensils placed in the open space at the top. In this connection it may be noted that the cooking top, as usual, is provided above the burners with removable lids 4a which, when removed, enable the utensils to be exposed directly to the burner flames, if desired.

In Figs. 4 and 5, the cooking top is made up of a marginal flange 23 extending entirely around the underlying heat generating chamber, and of two insert plates 24, it being noted that the burner plate 10 is suspended from the marginal flange at opposite sides of the range. This construction is intended to suggest the ready application of the present improvements to ranges of the open top variety which present a marginal flange like 23 and grid inserts in place of the plates 24. In other words, by substituting the insert plates 24 for the ordinary grids, and by adding the burner plate 10 with its appurtenant parts, an ordinary open top range may be readily converted into a closed top range of the improved form herein disclosed. Indeed, if desired, the present closed top range may be converted into an open top range by removing the insert plates 24 and substituting grids in place.

It will now be seen that, in the operation of the improved range, the flame jets of the several Bunsen burners are projected up through the secondary air nozzles into the combustion chamber and up against the underside of the closed cooking top, which is thus heated by direct contact with the burner flames. The flame jets when projected through the nozzle openings automatically control the quantity of air admitted into the combustion chamber, entraining only so much air as is required to support combustion. The action is that of an ejector, the secondary air openings functioning as ejector throat openings and the flame ports as ejector nozzles, with the result that the secondary air is being en-

trained by the flame jets is actually forced into the heat generating chamber so as to ensure the proper aeration of the flame jets for complete combustion without rendering it necessary to resort to the use of a forced chimney draft with its attendant objections. The air thus entrained is in its pure atmospheric condition and is in no way contaminated by the products of combustion. This is true under all conditions, that is to say whether one, two, three, or all four burners are in operation at a time, since the air which enters the open front of the secondary air chamber is free to pass to any one or all of the independent groups of nozzle openings for entrainment by the flame jets of the individual burners. As a result, even though all four burners are in operation at the same time, secondary air is supplied to the rear burners in ample quantity and in pure atmospheric condition and without hindrance or interference on the part of the front burners. The heated products of combustion are drawn out at the rear of the combustion chamber through the flue, and in escaping give up their heat to the cooking top and the burner plate, the heating capacity of the escaping products of combustion being greatly increased by the shallow character of the combustion chamber, due to the close proximity of the burner plate to the cooking top. The burner plate, becoming hot, will in turn radiate its heat to the overlying cooking top and aid further in promoting the heating efficiency of the range in this respect. Moreover, some of the heat radiated from the burner plate will be imparted to the air entering the underlying secondary air chamber and hence enable the air to be more effectively entrained at the flame ports. Once the cooking top is heated, one burner alone will keep it hot, since the combustion chamber is substantially co-extensive with the top and allows the heated products of combustion to be distributed uniformly throughout the entire under surface of the top. Again, the shallow character of the combustion chamber becomes important in bringing about such uniform heating of the top, the products of combustion being prevented from expanding unduly or in a way which would dissipate the heat units. The unobstructed character of the heat generating chamber is important in bringing about the above results and it is also important in providing for the proper expansion of the burning gases within said chamber, such expansion avoiding back pressure upon the flame ports or gas orifices as well as the secondary air discharge openings and thus allowing both primary and secondary air to be properly supplied to and mixed with the gas in a manner conducive to the greatest heating efficiency. Due to the restricted

character of the nozzle openings, the pressure of the products of combustion at the flame ports, notwithstanding the shallow character of the combustion chamber, is reduced to a minimum, thereby lessening the tendency to back pressure. Moreover, since the burners are protected from the heat of the products of combustion, there is less tendency to cause excessive expansion of the contained gas, and hence the entrainment of the primary air at the gas cocks is kept substantially uniform at all times. These and other advantages will now be readily apparent to those skilled in the art.

The invention is not, of course, confined to the precise construction shown and described, nor to any particular construction by which the same may be carried into effect, as many changes may be made in the details without departing from the main principles of the invention and without sacrificing its chief advantages. For instance, while the best results may be accomplished by providing a separate secondary air discharge opening for each of the flame ports, obviously substantially the same results may be obtained by making each secondary air opening large enough to serve two or more flame ports, so long as the relation between the enlarged air opening and the associated flame ports is such as to produce the ejector effect previously noted. It should be understood, therefore, that the invention is not limited to any specific form or embodiment, except in so far as such limitations are set forth in the appended claims.

Having thus described my invention, what I claim is, as follows:

1. A gas range including, in combination, a closed cooking top, Bunsen burners, each formed with a series of flame ports located beneath the front portion of said top, Bunsen burners of substantially the same type and size located beneath the rear portion of said top, and a burner plate arranged between the burners and the cooking top and forming in connection with the latter an unobstructed heat generating chamber having an outlet for the products of combustion, said burner plate being formed above each burner with a group of secondary air openings through which the flame jets project, the form and relation of said air openings and the flame ports being such that the latter will act as ejector nozzles and the former as ejector throat openings.

2. A gas range including, in combination, a closed cooking top, Bunsen burners located beneath the front portion of said top, Bunsen burners of substantially the same size located beneath the rear portion of said top, each burner being formed with a plurality of flame ports, and a burner plate arranged between the burners and the cooking top and forming in connection with the latter an un-

obstructed heat generating chamber having an outlet for the products of combustion, said burner plate being formed above each burner with a group of secondary air openings through each of which an individual flame jet projects.

3. A gas range including, in combination, a closed cooking top provided at its front with a plurality of removable lids and also 10 provided at its rear with a plurality of removable lids, a Bunsen burner located beneath each of the top lids and each formed with a series of flame ports, and a burner plate interposed between the several burners 15 and the cooking top and forming in connection with the latter an unobstructed heat generating chamber having an outlet for the products of combustion, said burner plate being formed above each burner with a 20 group of secondary air openings through which the flame jets project, the form and relation of said air openings and the flame ports being such that the latter will act as 25 ejector nozzles and the former as ejector throat openings.

4. A gas range including, in combination, a closed cooking top, Bunsen burners located beneath the front portion of said top, Bunsen burners of substantially the same size 30 located beneath the rear portion of said top and each burner being formed with a plurality of flame ports, and a burner plate arranged between the burners and the cooking top and forming in connection with the 35 latter an unobstructed heat generating chamber substantially co-extensive with the top and closed at the front and sides and open at the rear, and an exterior flue communicating with the rear open end of the heat generating chamber, the said burner plate being 40 formed above each burner with a group of secondary air openings through which the flame jets project, the form and relation of 45 said air openings and the flame ports being such that the latter will act as ejector

nozzles and the former as ejector throat openings.

5. A gas range including, in combination, a closed cooking top, Bunsen burners located beneath the front portion of said top, Bunsen burners of substantially the same size 50 located beneath the rear portion of said top and each burner being formed with a plurality of flame ports, and a substantially flat burner plate arranged between the burners and the cooking top in close parallel relation to the latter and forming in connection therewith a shallow, unobstructed heat generating chamber having an outlet for the products of combustion, said burner 60 plate being formed above each burner with a group of secondary air openings located in the plane of the plate through which the flame jets project and serving as ejector throat openings. 65

6. A gas range including, in combination, a closed cooking top, Bunsen burners located beneath the front portion of said top, Bunsen burners of substantially the same size 70 located beneath the rear portion of said top, each burner being formed with a plurality of flame ports, and a burner plate arranged between the burners and the cooking top and forming in connection with the latter a shallow, unobstructed heat generating chamber 75 substantially co-extensive with the top and having an outlet for the products of combustion, said burner plate being formed above each burner with a group of secondary air openings through which the flame jets 80 project, said air openings serving as ejector throat openings and the flame ports as ejector nozzles cooperating therewith, and the flame ports terminating below the lower ends of the air openings, as and for the 85 purpose described.

In testimony whereof, I have affixed my signature hereto.

HENRY W. O'DOWD.
